KARL D. SAULPAW, OF CALHOUN, TENNESSEE, ASSIGNOR OF ONE-HALF TO GEORGE L. SAULPAW, OF CALHOUN, TENNESSEE.

FLY-SWATTER.

1,164,875.

Specification of Letters Patent.

Patented Dec. 21, 1915.

Application filed July 28, 1914. Serial No. 853,657.

To all whom it may concern:

Be it known that I, KARL D. SAULPAW, citizen of the United States, residing at Calhoun, in the county of McMinn and State 5 of Tennessee, have invented certain new and useful Improvements in Fly-Swatters, of which the following is a specification.

This invention relates to certain new and useful improvements in that class of devices 10 commonly known as "fly swatters" and has as its primary object to provide an article of this character including a flexible reticulated body portion and a support or handle therefor, and wherein a flexible element will 15 be interposed between the body portion and the handle so that, in use, the said flexible element will form a hinge between the body portion and the handle.

The invention has as a further object to 20 provide a device of this character wherein the flexible element will bend transversely at the adjacent extremity of the handle so that, in use, the reticulate body portion will be moved as an entirety and will thus be relieved of the strain incident to the flexing 25 thereof which would otherwise occur were the body portion directly connected to the handle.

A still further object of the invention is 30 to provide a device of this character which will be simple in construction and wherein the flexible element interposed between the handle and the body portion may be readily connected to the body portion and to the handle. And the invention has as a still further object to provide a device of this character wherein the flexible element interposed between the handle and the body portion will be of sufficient rigidity to effectually 35 support the flexible body portion transversely, and will also possess a degree of flexibility so as to readily bend or flex transversely when the "swatter" is moved in the practical use of the device.

With these and other objects in view, my 40 invention will be more fully described, illustrated in the accompanying drawings and then, specifically pointed out in the claims which are attached to and form a part of 45 this application.

In the accompanying drawings:—Figure 1 is a perspective view of my improved device, the handle thereof being shown partly

broken away, Fig. 2 is a longitudinal sectional view thereof, particularly illustrating 55 the construction of the flexible element interposed between the body portion of the device and the handle, Fig. 3 is a top plan view of a modified form of the invention, Fig. 4 is a fragmentary longitudinal sectional view of such modified form, and Fig. 5 is a fragmentary bottom plan view showing the inner extremity of the handle with the attaching plate in position thereon, the head engaged by the handle not being illus- 60 trated.

Corresponding and like parts are referred to in the following description and indicated in all of the views of the drawing by the same reference characters.

Devices of this character as constructed heretofore, have usually included a body portion of flexible wire cloth to which is directly connected at one edge thereof a rigid handle, in some instances, the handle being 75 provided with a transversely disposed rigid head arranged to embrace the adjacent end edge of the wire cloth. The result of this construction has been that, when the handle is moved in an arc, in the practical use of 80 the device, the wire cloth is caused to flex or bend transversely immediately adjacent the handle or adjacent the rigid head referred to, and has as a result with but slight usage, become broken at such points, the continued flexing of the wire cloth causing the longitudinally extending wires thereof to break immediately adjacent the head or the handle to thus very soon impair the efficiency 85 of the device and thereafter to result in its 90 entire disuse. Furthermore, when the longitudinally disposed wires of the wire cloth forming the body portion have thus become broken, the ends of such wires project laterally and when the swatter is then struck 95 against a piece of cloth or other fabric, the projecting ends of said wires will stick into the fabric to become engaged therewith, resulting in annoyance and often further resulting in injury to the cloth or fabric. 100

The present invention, therefore, seeks to provide a construction wherein these various disadvantageous features will be overcome and wherein the durability and the efficiency of the device will be prolonged and enhanced.

Referring more particularly to the drawings, the numeral 10 designates the handle or support of my improved device which may be of any desired size or configuration and which may be constructed of any suitable material. The handle or support 10 is preferably slotted at one end to receive the head or flexible element indicated as a whole at 11.

10 The head 11 preferably includes the superposed sections or sheets of leather 12 and 13 and may be of any desired size or configuration. However, in the drawings, I have shown the head as substantially triangular, being cut away upon its rear edges as at 14, since by this construction a saving in material is effected, while the appearance of the device is enhanced. Interposed between the sections 12 and 13 adjacent the inner extremity of the head, is a stiffening plate 15. The stiffening plate 15 is preferably formed from a piece of relatively thin resilient sheet metal and is of such shape as to conform to the shape of the head, the said plate being best illustrated in Fig. 1 of the drawings. The stiffening plate 15 is of such rigidity as to effectually reinforce the head 11 adjacent the inner extremity of the handle. Preferably the sections 12 and 13 are connected by 30 a line of stitching 16 which extends transversely through the said sections immediately adjacent the edges of the plate 15, the said line of stitching thereby serving to maintain the plate 15 in position.

35 Connecting the head 11 with the handle 10 are a plurality of longitudinally spaced rivets or other suitable fastening means 17, which extend transversely through the adjacent extremity of the handle and through 40 the head, the said rivets being each overturned at one end to engage a metallic reinforcing strip 18. Where a wooden handle is employed, the use of the metallic reinforcing strip 18 is preferable and said strip is 45 arranged to extend longitudinally of the handle 10 at the inner extremity thereof and coincident with the slot formed in said handle to receive the head 11. As shown in Fig. 2 of the drawings, the reinforcing strip 50 18 is flat and is disposed to seat against the adjacent flat face of the handle, the said strip being preferably enlarged at one end to bear laterally over the adjacent face of the handle at the inner end thereof.

55 It is now desired to bring attention to the fact that while I have indicated above that the head 11 is preferably formed of leather, still it will be readily understood that any other suitable material may be readily employed, such as heavy fabric, it being intended that the said material shall possess sufficient rigidity to operatively support the body portion or foraminous element of the "swatter", and at the same time, be possessed 60 of sufficient flexibility so as to form a hinge

between said body portion and the handle of the device, and I therefore, do not wish to limit myself in this regard.

Connected with the head 11 is the reticulate body portion 19, the said body portion 70 being preferably formed from a piece of suitable wire fabric, one end edge of which is preferably overlapped, as shown, and disposed between the overlapping edges of the head 11 at the outer extremity thereof, and 75 is secured thereto, by a plurality of lines of stitching 20. Midway the side edges thereof, the body portion 19 is reinforced by spaced longitudinally extending spines 21 between which the longitudinally extending wires of the fabric are omitted. Each of the said spines 21 is preferably formed by weaving a plurality of the longitudinally extending wires of the fabric together. By this construction, the body portion 19 is reinforced longitudinally and any tendency of the body portion to break transversely intermediate its ends is overcome.

Arranged upon the outer end edge of the body portion 19, which is turned back upon itself, as illustrated, and extending transversely thereof, is a binding 22 of fabric or other suitable material, the said binding being secured to the body portion preferably by stitching 23. The body portion 19 is thus 95 prevented from fraying at its free end, and in overlapping the ends of the body portion, a more secure connection is had between the said body portion and the head 11 and the binding 22.

100 As best shown in Fig. 2 of the drawing, the inner edge of the body portion 19 terminates in spaced relation to the adjacent extremity of the handle 10 and the head 11 being formed of flexible material, it will be 105 clear that the said head will readily bend transversely when the handle 10 is moved in the path of an arc, in the practical use of the device, to strike with the body portion 19. It will also be clear that the head 11 will 110 thus form a hinge between the handle 10 and the body portion 19 of such character as to take up all transverse flexing movement under such circumstances, between the handle 10 and the body portion 19 so that the body 115 portion 19 will move practically as an entirety. Any tendency of the body portion 19 to break transversely at its juncture with the head 11 will be overcome and the durability of the device will thus be greatly enhanced. 120 Furthermore, owing to the presence of the flexible element or head 11, the body portion 19 may be more readily moved in the practical use of the device to strike successfully.

125 In Figs. 3 and 4 of the drawings, I have illustrated a modified form of the invention wherein I provide a metallic head 24, the said head being preferably formed from a piece of suitable sheet metal bent upon itself and secured within the slotted end of the 130

handle 10 by suitable rivets or other fastening means 25. In this form of the invention, the head 24 is preferably of a like configuration to that illustrated in the preferred 5 form of the invention, and in securing the head 24 to the handle 10, the reinforcing strip 18 may be omitted, if desired. Preferably, I interpose a filling block 26, which may be formed of leather or any other 10 suitable material, between the overlapping portions of the head 24 adjacent the inner extremity thereof and secured between the overlapping portions of the head adjacent its outer extremity, is a flexible element or 15 hinge 27. The hinge 27 is preferably formed from suitable pieces of leather as in the preferred form of the invention which are connected with the head 24 in any suitable manner as by rivets 28. Arranged between 20 the overlapping portions of the hinge 27, adjacent its outer extremity, is the body portion 19, the said body portion 19 being connected at one end edge thereof, with the hinge 27, preferably by stitching. The form 25 of the invention shown in this modification is otherwise constructed in accordance with the preferred form of the invention and a further description thereof will not, therefore, be given. However, it will be ob- 30 served that the hinge 27 will provide a flexible connection between the body portion 19 and the handle 10 and that the metallic head 24 will effectually support said hinge and is so arranged as to not come in contact with 35 the body portion 19 to cause it to crease transversely when flexed and thus become broken.

It will therefore be seen that I provide a very simple and efficient construction for 40 the purpose set forth wherein the foraminous body portion of the device is operatively connected with the handle in such manner that the said body portion will not be caused to crease transversely when 45 flexed. It will further be seen that the flexible element interposed between the body portion and the handle is of such character, that while being adapted to bend freely, in the practical use of the device, 50 will, nevertheless, effectually support the body portion to provide for the quick and accurate movement thereof.

Copies of this patent may be obtained for five cents each, by addressing the "Commissioner of Patents, Washington, D. C."

Having thus described my invention, what I claim and desire to secure by Letters Patent is:—

55

1. A device of the character described including a support providing a handle, a body portion, and a yieldable connection between the body portion and the handle, said connection including superposed layers of 60 flexible material secured together.

2. A device of the character described including a handle, a body portion, a yieldable connection between the body portion and the handle, and a stiffener for said 65 yieldable connection, said yieldable connection including superposed layers of flexible material secured together.

3. A device of the character described including a handle, a body portion, and a connection of relatively limp material interposed between one edge of the body portion 70 and the handle.

4. A device of the character described including a handle, a body portion, a connection of relatively limp material between the handle and the body portion, and a stiffening plate arranged to coact with said connection.

5. A device of the character described including a handle, a head carried by the handle, and a body portion carried by said head, the head being formed of pliable material and providing a yieldable connection between one edge of the body portion and 80 the handle.

6. A device of the character described including a handle, a head carried by the handle and formed of superposed layers of relatively limp material, and a body portion carried by the head.

90

7. A device of the character described including a handle, a head carried by the handle and formed of superposed layers of flexible material, a stiffening plate interposed 95 between the layers of material of the head, and a body portion carried by the head.

In testimony whereof I affix my signature in presence of two witnesses.
